UNITED STATES PATENT OFFICE.

MOSES A. WOOLDRIDGE, OF WYACONDA, MISSOURI.

RAILROAD GRADE-CROSSING.

1,230,058.

Specification of Letters Patent. Patented June 12, 1917.

Application filed October 2, 1916. Serial No. 123,309.

To all whom it may concern:

Be it known that I, Moses A. Wooldridge, a citizen of the United States, residing at Wyaconda, in the county of Clark and State 5 of Missouri, have invented new and useful Improvements in Railroad Grade-Crossings, of which the following is a specification.

This invention relates to an improvement 10 in railroad grade crossings, and the object is to provide a plurality of metallic plates so located with respect to the rails that vehicles may cross the tracks, and which plates will not be liable to become displaced and 15 interfere with railway traffic.

The invention consists of certain novel features of construction and combinations of parts which will be hereinafter described and pointed out in the claims.

20 In the accompanying drawing:—

Figure 1 is a view in top plan of the invention;

Fig. 2 is a transverse vertical sectional view;

25 Fig. 3 is a longitudinal vertical sectional view through the central plates and support; and

Fig. 4 is a perspective view of the central plate slightly modified.

30 A, represents the ties, and B the two rails, which may be fastened to the ties in the usual manner.

Located between the rails B, and parallel therewith are a pair of wooden bars 1. The 35 bars are of sufficient height to support a plate 2, made preferably of heavy slab iron or malleable iron, in the proper plane with the upper surface of the ball or tread of the rails B.

40 The plate 2 is preferably made of such a length as to accommodate the traffic, but several lengths may be employed when found desirable. The plate 2 and bars 1, are fastened to the ties A, by means of bolts, 45 screws or spikes 3 which pass through the plate, and bars, into the ties for rigidly maintaining the plate and bars in position.

The longitudinal edges of the plate 2 are bent downwardly and then upwardly so that 50 the edges lie beneath the ball or tread of the

rails, forming a trough or groove 10 along each side of the plate, so that there is no interference with the travel of traffic over the rails, and insures against the packing of dirt and gravel between the plate and rails, 55 and any water will flow off, so that the plate is practically self-cleaning against the lodging of sleet and snow.

Inclined plates 4 are located at the ends of the bars 1, and are fastened to the bars 60 and ties by means of bolts or screws 5. The plates form a means to prevent anything hanging from the car or trucks engaging the plate 2 and causing its disarrangement.

Located along the outer surface of each 65 rail B, and parallel therewith are wooden bars 6, to which are connected inclined plates 7, by means of bolts or screws 8, which pass through the plates and bars and into the ties A for fastening them in position. The outer or lower edges of the plates 70 are connected to the ties by bolts, spikes or screws 9.

The plates 2 and 7 are each provided with angle iron braces 12 and 11, respectively, 75 which are connected to lower surfaces thereof by rivets, and extend transversely therefrom.

It may be advisable in some instances to 80 omit the grooves or troughs 10 from the central plate 2, and simply allow the edges of the plate to extend down between the rails and bars, as shown in Fig. 4.

From the foregoing it will be seen that a 85 very simple construction is provided which can be readily applied, or removed as occasion demands.

I claim:—

1. A railroad grade crossing, comprising 90 ties and rails, bars located between and along the outer surfaces of the rails and extending parallel therewith, of a plate supported on the bars between the rails, and inclined plates connected to the bars located along the outer surfaces of the rails, and 95 means passing through the plates, and bars and into the ties for fastening them in place.

2. A railroad crossing, comprising ties and rails, bars located between and along the outer surfaces of the rails and extend- 100

ing parallel to the rails, a plate supported on the bars between the rails, the edges of the plate being bent so that they are located beneath the tread of the rail, inclined 5 plates engaging the ends of said bars and resting on the ties for forming a protection for the ends of the plate, inclined plates

supported on the bars located on the ties along the outer surface of the rails, and means passing through said plates and bars 10 and into the ties for fastening the bars and plates in position.

MOSES A. WOOLDRIDGE.
